ROBERT J. PAYNE, OF FREDERICKSBURG, VIRGINIA

SLING

Application filed July 2, 1925. Serial No. 41,187.

When a broken clavicle is set, it is very necessary that the shoulder of the patient be maintained at the proper normal height, and it has been the custom to bandage the arm 5 tightly in order to maintain the proper position of the parts, while the broken bone knits.

The object of the present invention is to provide a simple but very effective sling, which will support the arm so as to maintain 10 the shoulder at the proper elevation, said sling holding the arm without undue confinement and moreover being so constructed that it may be entirely removed when the patient is lying down, in which position a support is 15 ordinarily unnecessary.

In the accompanying drawings:

Figure 1 is a rear elevation of a person having the sling applied thereto,

20 Figure 2 is a front elevation of the same, Figure 3 is a perspective view of the sling,

Figure 4 is a sectional view taken substantially on the line 4—4 of Figure 1.

The body of the sling consists of a strip of cloth, as canvas or other flexible material, 25 this strip being doubled between its ends and forming opposite extended walls 5. The bight of the strip constitutes an elbow-receiving pocket, and this pocket preferably has side walls 6 of cloth that are overturned 30 against the outer sides of the end walls and are sewed or otherwise secured thereto. The free end of one of the end walls 5 is provided with one or more buckles 7, and the corresponding end of the other wall has straps 8.

35 In using the device the pocket 6 is suitably padded and receives the elbow of the arm below the broken collar-bone. The sling passes diagonally over the opposite shoulder, as illustrated, and the ends of the end walls 40 are buckled together as clearly shown in Figure 2. It will thus be evident that the shoulder will be supported by the upper arm, the forearm being held behind the front end wall. It has been found that this sling constitutes an effective support for the purpose, 45 and when the patient lies down it may be readily removed, leaving the arm free.

From the foregoing, it is thought that the 50 construction, operation and many advantages of the herein described invention will be ap-

parent to those skilled in the art, without further description, and it will be understood that various changes in the size, shape, proportion and minor details of construction may be resorted to without departing from 55 the spirit or sacrificing any of the advantages of the invention.

What I claim, is:

A sling for supporting the arm and shoulder associated with a broken clavicle which 60 comprises a single strap of sufficient length to extend along the forearm, beneath and around the elbow, thence diagonally upward on the back and over the shoulder, means for detachably securing the ends of the strap together, said strap being broad enough to 65 substantially cover and support the forearm, and side walls carried by the margins of the strap at the bend of the elbow and forming a pocket for the elbow.

70 In testimony whereof, I affix my signature.

ROBERT J. PAYNE.
